UNITED STATES PATENT OFFICE.

GEORGE MILES, OF WELLESLEY HILLS, MASSACHUSETTS.

PNEUMATIC DISPATCH APPARATUS OR MECHANISM.

SPECIFICATION forming part of Letters Patent No. 294,899, dated March 11, 1884.

Application filed September 25, 1882. (No model.)

To all whom it may concern:

Be it known that I, GEORGE MILES, of Wellesley Hills, in the county of Norfolk, of the State of Massachusetts, have invented a new and useful Improvement in Pneumatic Dispatch Apparatus or Mechanism; and I do hereby declare the same to be described in the following specification and represented in the accompanying drawings, of which—

10 Figure 1 is a side elevation of a dispatch apparatus of my improved kind. Fig. 2 is a front view, and Fig. 3 a transverse section, of one of its receivers as open. Fig. 4 is a longitudinal section of one of the air-cocks.

15 The nature of my invention is duly set forth in the claim hereinafter presented.

In Fig. 1, A represents a closed air-reservoir, having an eduction-pipe, a, leading vertically out of it at top, and provided with a stop-cock, b, a section of which is given in Fig. 4. In this cock the valve-spindle c is represented as provided with a spring, d, for closing the valve e upon its seat f in the partition g, such spindle having at its outer end 25 a knob, h. The stop-cock b opens into a dispatch-receiver, B, which, like other such receivers C, D, and E, as shown in Fig. 1, has a mouth, i, provided with a door, k, to be closed either by a spring, l, and a latch, m, as and 30 arranged in manner as represented in Figs. 2 and 3, or by other suitable devices. From the receiver B a vertical tube or dispatch-conduit, F, extends. A branch pipe, G, opens obliquely out of the eduction-pipe a, and leads 35 into a stop-cock, b', like the stop-cock b. Such stop-cock b' opens into the receiver C, from which a dispatch-conduit, F', leads. From the branch pipe G two branch pipes, H I, lead horizontally, and communicate with the two 40 stop-cocks b² and b³, each of which opens into one of the two dispatch-receivers D and E, which communicate with each other by a dispatch-transmitting tube, M.

P is an air force-pump, whose eduction-pipe n opens into the air-reservoir A. The piston of such pump is operated by a steam-engine, N, whose induction-pipe o has in it a cock, p, having its valve-spindle connected by a rod, q, with the shorter arm of a lever, r, 50 the longer arm of said lever being provided with a movable weight, s. The said longer

arm is connected by a link, t, with the piston of a small upright cylinder, u, into which, at its bottom, a pipe, v, leading from the air-reservoir A, opens. The cylinder u is to be supported by a column, w, or by other suitable means. On the air being withdrawn from the reservoir A, the piston in the cylinder u will fall therein and cause the valve of the cock p to move so as to allow steam to be admitted 55 to the cylinder of the engine, in order to put the engine in action for the working of it, and the air-pump to effect the necessary supply of air to the reservoir. Each dispatch or transmitting conduit F and F' leading from 60 the receivers B and C is at its further end to be provided with a receiver, a stop-cock, and an auxiliary air-tube, like those marked E, b², and L, from which it will be seen that each transmitting pneumatic circuit is composed 65 of a transmitting-conduit, two receivers at the ends thereof, two stop-cocks to such receivers, and a pipe leading from each of such cocks to the air-reservoir, or a pipe communicating either directly or indirectly there- 70 with. In using the said circuit for transmission of a parcel or a box to fit and slide in the transmitting-tube of the circuit, the two receivers being open, the box or parcel is to be placed in one of them, after which it is to 75 be closed. The stop-cock of such receiver is next to have its valve forced off its seat, in order for air from the reservoir to enter the receiver and drive the box or parcel therefrom into and through the transmitting-tube 80 and to and into the other or distant receiver. This having taken place, the said valve of the said cock is to be closed and the door of the first receiver is to be opened. In this way a box or parcel may be sent either way through 85 the circuit, an amount of air equal to that expended in effecting such being immediately supplied to the reservoir by the air-pump, whose motor or steam-engine will be put in operation by reason of the fall of the piston of 90 the cylinder u.

The pipe v, cylinder u, its piston, the lever r, weight s, and rod q, applied to the stem of the steam-cock p, constitute what I term the "regulator" or "engine-starter," which constitutes an important element of my invention.

I am aware that an air-compressing engine

has been provided with a device which regulates the working mechanism so as to control the supply of air. I make no claim to an automatic starter or regulator, considered broadly or in itself.

What I claim is as follows, viz:

The combination of the regulator or engine-starter, substantially as set forth, with the

steam-engine, air-pump, air-reservoir, and one or more pneumatic dispatch-transmitting circuits, as described, all being adapted and to operate essentially as set forth.

GEORGE MILES.
